United States Patent Office

Des. 219,831
Patented Feb. 2, 1971

219,831

DIGITAL CLOCK RADIO

Kaoru Eguchi, 70-25 Yellowstone Blvd.,
Forest Hills, N.Y. 11375

Filed Jan. 29, 1970, Ser. No. 21,134

Term of patent 3½ years

Int. Cl. D10—01

U.S. Cl. D42—7

FIG. 4.FIG. 3.

FIG. 1 is a bottom isometric view of a digital clock radio showing my new design;

FIG. 2 is a top isometric view from the opposite side;

FIG. 3 is a top isometric view of a digital clock radio showing another form of my new design; and,

FIG. 4 is a bottom isometric view thereof from the opposite side.

I claim:

The ornamental design for a digital clock radio, substantially as shown and described.
